DOLL EYE UNIT

Filed Sept. 26, 1934

UNITED STATES PATENT OFFICE

2,072,358

DOLL EYE UNIT

Matteo De Cesare, Newark, N. J., and David Cohn, Brooklyn, N. Y., assignors of one-third to said Cohn, one-third to Sam Kalner, and one-third to Karl Ohlbaum, New York, N. Y.

Application September 26, 1934, Serial No. 745,558

14 Claims. (Cl. 46—169)

This invention relates to doll eye units.

An object of this invention is to provide a doll eye unit having means for yieldingly pressing the doll's eyes into the sockets of the doll's head and adjusting the yielding pressure on said eyes.

A further object of this invention is to provide a doll's eye unit which may be readily and simply assembled within the doll's head.

A further object of this invention is to provide in a doll's eye unit of the character described improved means to prevent the doll's eyes from falling out of the sockets of the doll's head.

Another object of this invention is to provide a doll eye unit of the character described which shall be relatively inexpensive to manufacture, smooth and positive in operation and, withal, practical and efficient to a high degree of use.

Other objects of this invention will in part be obvious and in part hereinafter pointed out.

20 The invention accordingly consists in the features of construction, combination of elements, and arrangement of parts which will be exemplified in the construction hereinafter described, and of which the scope of application will be indicated in the following claims.

In the accompanying drawing, in which is shown one of the various possible embodiments of this invention,

Fig. 1 is a cross-sectional view of a doll's head 30 provided with a doll eye unit embodying the invention;

Fig. 2 is a cross-sectional view taken on line 2—2 of Fig. 1;

Fig. 3 is a top elevational view of our improved 35 doll eye unit;

Fig. 4 is a view similar to Fig. 1 and illustrating another form of our invention;

Fig. 5 is a cross-sectional view taken on line 5—5 of Fig. 4; and

40 Fig. 6 is a cross-sectional view taken on line 6—6 of Fig. 4.

Referring now in detail to the drawing, 10 designates a doll's head and mounted within said head is a doll eye unit 12 embodying the invention. The doll's head 10 may be formed of a front molded portion 13 and a rear molded portion 14, part of which only is shown in the drawing. Portions 13 and 14 are attached together along the seam 15. Said head portion 13 is formed with eye sockets 11a and with a recess 18 on the inner surface thereof in back of the forehead. The rear edge of the front portion 13 is formed on opposite sides thereof with notches 16 and received within said notches is a horizontal cross rod 17. The rod 17 is fixed in place upon

assembling the front and rear portions 13 and 14 of the doll's head. Supported by the rod 17 and within recess 18 is a rail member 20 having a top wall 21 and side walls 22. The front end of the member 20 is received within the recess 18. Adjacent the rear end of the member 20, the side walls 22 are formed with aligned openings 23 receiving therethrough the rod 17. The rod may have prongs 17a formed thereon on opposite sides of rail 20 to retain said rail centrally 10 located. It will be noted that the rail 20 is horizontal and extends from front to rear centrally of the doll's head.

The top wall 21 of the member 20 is formed with a longitudinal slot 24, for the purpose hereinafter appearing. Slidably received within the rail member 20 is a member 25 made of an elongated strip of resilient metal and having a portion 26 contacting the underside of the wall 21 and being formed with an opening 27. Extending from said portion 26 is a portion 25 projecting downwardly and being formed with a channel shaped portion 30 adjacent the lower end thereof. There is also received within the rail member 20 a stop or backing member 31 made of an elongated strip of metal, preferably heavier than the metal of which the member 25 is made. Said member 31 has a portion 32 contacting the underside of the portion 26 of member 25 and formed with a through opening 30. Extending downwardly from the portion 32 is a portion 34. For fixing the members 25 and 31 to the rail member 20 a screw 37 extends through the openings 27 and 33 and is provided with a head 38 at the lower end thereof. A washer 39 formed with a screw threaded opening receives the upper end of the screw. The shank of the screw extends through the slot 24 of the rail member 20. It will now be understood that the members 25 and 31 may be attached to the member 20 by tightening the screw 37. For this purpose the head 35 of said screw is formed with a kerf on the underside thereof. It will be noted that the members 25 and 31 are fixed, one with respect to the other, by reason of the shank of the screw extending through the openings 27 and 34. However, said members may be moved together forwardly or rearwardly by loosening the screw 37 to adjust the position thereof with respect to said rail. 45 50

Rotatably mounted within the head in a manner hereinafter appearing is a swinging eye device 41. Said device comprises a pair of preferably hollow semi-spherical eye balls 42 pressed within the eye sockets 11 and mounted on the ends of a 55

bridge 43 received within and engaged by the channel shaped portion 39 of the member 25. The bridge 43 may be of square cross section and the eye ball members 42 formed with square 5 shaped diametric openings receiving said bridge therethrough. Opposite ends of the bridge 43 may be upset as at 44 to retain the eye ball members 43 thereon.

Fixed to the bridge 43 is a U-shaped strap 45, 10 to the rear of which there is riveted or fixed in any other suitable manner a metal strip 47, having a weight 48 on the lower end thereof. A small loop or band 49 of rubber encircles a portion of the strip 47 and is adapted to contact a projection 15 50 on the inner surface of the head portion 13 adjacent the rear of the chin and serving as a shock absorber when the device 41 swings in a clockwise direction, looking at Fig. 1 of the drawing. The strip 47 is provided with a rearwardly 20 and downwardly projecting end portion 52 adapted to contact the portion 34 to the member 31 when the bridge and weight swing in a counter-clockwise direction, looking at Fig. 1 of the drawing, to limit rotation of the eye members 42 25 within the sockets.

It will now be understood that the yielding pressure of the eye balls 42 within the eye sockets may be adjusted by positioning the members 25 and 31. Normally, the bridge 43 contacts the 30 rear side 30a of the channel shaped portion 30. Should the doll's head receive a severe shaking, or should the eye balls 42 be poked through the eye openings of the doll's head, the bridge 43 will be moved rearwardly against the tension of the 35 spring member 28 until the latter contacts the stop 34. In such position the bridge 43 cannot fall down or pass downwardly between the front of the doll's head and the spring 28, by reason of engagement of the bridge with the lower side 40 of the channel shaped portion 30. The upper side of the channel shaped portion also serves to limit a violent upward throwing of the device 41.

In Figs. 4, 5 and 6 there is illustrated another 45 form of our invention. As shown in Figs. 4, 5 and 6, the doll's head 10a is likewise formed with a front portion 13 and a rear portion 14, the front portion being formed with notches 16 for receiving a horizontal rod 17. The front portion 50 13 of the head is likewise formed with a recess 18 on the inner surface thereof and in back of the forehead. Supported by the rod 17 and head portion 13 is a bifurcated substantially U-shaped member 60 made of resilient metal and having 55 a pair of parallel arms 61 interconnected at one end as at 69, the said interconnecting end being received within the recess 18. The outer ends of the arms 61 are formed with openings receiving the rod 17 therethrough. The arms 61 may 60 be pressed toward each other, but movement of said arms away from each other is limited by upset portions or prongs 63 on the rod 17. Said parallel arms 61 are formed with aligned openings 64 in intermediate portions thereof, for the 65 purpose hereinafter appearing.

Slidably mounted on and receiving arms 61 is 70 a member 65 having a bottom wall portion 66, side wall portion 67 and inwardly extending flanges 68 at the top contacting the upper edges of the arms 61. Extending forwardly and downwardly from the bottom wall 66 of the member 65 is a tongue 69. The position of the member 65 on the arms 61 may be fixed by a pair of tabs 70 extending from the side walls 67 and being received within the openings 64 in said

arms. The member 65 may be slidably moved on said arms by first pressing the arms 61 together to release the tabs 70 from the openings 64.

Riveted or otherwise fastened to the tongue 5 67 is a member 72 made of an elongated strip of resilient sheet metal. The member 72 comprises a portion 73 riveted to the tongue 69, as at 74 and having an end portion 75 extending downwardly below the tongue. The portion 73 is inclined upwardly and rearwardly and extends above the arms 61. Extending from said portion 73 is a downwardly folded portion 77 having a channel shaped portion 78 adjacent the lower end thereof. Extending from the lower end of 10 the portion 77 is a rearwardly extending portion 79 and projecting upwardly from said portion 79 is an upwardly extending portion 80 adapted to contact the rear surface of said lower end 75 of the portion 73. A swinging doll's eye device 15 41, similar to the swinging doll eye device shown in Fig. 1, may be mounted within the head 10a, the bridge 43 being received within the channel shaped portion 73 of the spring member 72 and contacting the rear side of said channel shaped portion. 20 25

It will now be noted that the spring portion 77 presses the doll eye members 42 into the eye sockets 11 of the doll's head 10a. The lower end 30 75 of the member 72 acts as a stop to limit rearward movement of the spring portion 77, in case of shaking of the doll or poking of the eye members 42. The top and bottom sides of the channel shaped portion 78 serve to limit upward or downward movement of the bridge 43 for retaining the eye members 42 within the sockets and to prevent falling out of the device 41. After the member 72 is riveted to member 65, a plurality of such inter-riveted members may be packed and shipped without the danger of interlocking, 35 40 45 the engagement of the portions 80 with the lower ends 75 of each member 72 preventing such interlocking engagement.

Our improved doll eye units may be readily 50 assembled in the doll's head. Referring first to the assembly of the structure shown in Figs. 1, 2 and 3 of the drawing, members 25 and 31 are mounted on the rail 20, the screw 38 being loosened, however, and the said members 25, 31 55 pushed rearwardly with respect to the rail member. The rod 17 is then passed through the openings 23 and the prongs 17a formed on the rod. The rail member 20 and rod 17 are then placed in position on the front portion 13 of the doll's head, with the ends of the rod 17 received within the notches 16 and the front end of the rail 20 received within the recess 18. The rear portion 14 of the doll's head is then fixed at the front portion, thus fixing within the head said rail and rod. The swinging eye device 41 is then placed within the doll's head by inserting same through the neck of the doll's head with a suitable instrument, to position the eyes 42 in sockets 11. A screw driving tool may then be inserted through the neck of the doll's head and members 25, 31 pushed forwardly to cause the spring portion 28 of the member 25 to resiliently press against the bridge 43. With the members 25 and 31 in proper position, the screw 37 is tightened by said tool to fix the members 25, 31 against 60 65 70 sliding movement on the rail member.

Referring now to the assembly of the construction shown in Figs. 4, 5 and 6, the member 65 is first assembled with the rod and placed in position on the front portion 13 of the doll's head. 75

The sliding member 65 is preferably disposed at the rear end of the rail adjacent the rod 17. This may be done by pressing the arms 61 toward each other and sliding the member 65 rearwardly. The rear portion 14 of the doll's head may then be fixed to the front portion to also fix within the head the rod 17 and the member 16. The swinging eye device 41 is then placed within the head through the neck thereof and positioned to bring the eye members 42 within the sockets 11. With a tool inserted through the neck of the doll's head, the sliding member 65 may then be pushed forwardly until the tabs 18 snap into the openings 64 of the arms 61. In such position the spring portion 77 resiliently presses the eyes into the sockets.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawing is to be interpreted as illustrative and not in a limiting sense.

What we claim is:—

1. In combination with a doll's head, a rail member fixed within the head extending from the front of said head rearwardly, a member slidably mounted on the first member, a bridge having doll's eyes received within the sockets of the doll's head, and resilient means associated with said slidably mounted member for pressing the doll's eyes within said sockets, said bridge being movable bodily toward and away from the front of the doll's head and relatively to said rail member and slidable member.

2. In combination with a doll's head, a member within the head extending from front to rear, a member slidably mounted on the first member, a bridge having doll's eyes received within the sockets of the doll's head, means associated with said slidably mounted member for resiliently pressing the doll's eyes within said sockets, said bridge being movable bodily toward and away from the front of the doll's head and relatively to said rail member and slidable member, said resilient means comprising a spring having a channel adjacent the free end thereof for engaging the portion of the bridge between the eyes.

3. In combination with a doll's head, a member within the head extending from front to rear, a member slidably mounted on the first member, a bridge having doll's eyes received within the sockets of the doll's head, means associated with said slidably mounted member for resiliently pressing the doll's eyes within said sockets, said bridge being movable by said resilient means relatively to said slidably mounted member, and means for retaining said slidably mounted member against sliding movement.

4. In combination with a doll's head provided with a pair of eye sockets, a member fixed within said head and extending from front to rear thereof, a member slidably mounted on said first member, a spring having a channel portion adjacent one end thereof and mounted on said second member, a pair of doll's eyes mounted on a bridge and received within said eye sockets, said spring member being adapted to engage said bridge at said channel portion for yieldingly pressing said eyes within said sockets, said

bridge being movable relative to said slidably mounted member.

5. In combination with a doll's head provided with a pair of eye sockets, a member fixed within said head and extending from front to rear thereof, a member slidably mounted on said first member, a spring on said second member, a pair of doll's eyes mounted on a bridge and received within said eye sockets, said spring being adapted to engage said bridge for yieldingly pressing said eyes within said sockets, said bridge being movable relative to said slidably mounted member, and stop means to limit rearward movement of said spring.

6. In combination with a doll's head provided with a pair of eye sockets, a member slidably mounted within said head for movement from front to rear with respect to said head, a strip spring fixed to said member, a pair of doll's eyes mounted on a bridge, said spring having a portion engaging a portion of the bridge between the eyes.

7. In combination with a doll's head provided with a pair of eye sockets, a spring slidably mounted within said head for movement from front to rear with respect to said head, a pair of doll's eyes mounted on a bridge, said spring comprising an elongated strip of resilient material and having a channel-shaped portion engaging a portion of the bridge between the eyes, and means for fixing said spring against sliding movement.

8. In combination with a doll's head provided with a pair of eye sockets, a spring slidably mounted within said head for movement from front to rear with respect to said head, a pair of doll's eyes mounted on a bridge, said spring comprising an elongated strip of resilient material and having a channel-shaped portion engaging a portion of the bridge between the eyes, means for fixing said spring against sliding movement, and stop means to limit flexing of said spring.

9. In combination with a doll's head provided with a pair of eye sockets, a member fixed within said head and extending from front to rear thereof and provided with an elongated slot, a spring contacting said member provided with an opening, a screw extending through said opening and slot and engaging a washer whereby said spring may be fixed to said member in various adjusted positions, a pair of doll's eyes mounted on the ends of a bridge and received within said sockets, said spring having a portion engaging the bridge between the eyes for yieldingly pressing said eyes within said sockets.

10. In combination with a doll's head provided with a pair of eye sockets, a member fixed within said head and extending from front to rear thereof and provided with an elongated slot, a spring contacting said member provided with an opening, a screw extending through said opening and slot and engaging a washer whereby said spring may be fixed to said member in various adjusted positions, a pair of doll's eyes mounted on the ends of a bridge and received within said sockets, said spring having a portion engaging the bridge between the eyes for yieldingly pressing said eyes within said sockets, and a stop member fixed to said first member to limit rearward flexing of said spring.

11. In combination with a doll's head provided with a pair of eye sockets, a horizontal rod fixed within said head and having the ends thereof engaging the side walls of said head, said head

- being formed with a recess on the inner surface thereof in back of the forehead, a bifurcated member having a pair of parallel arms interconnected at one end, said interconnected end being received within said recess, and the outer ends of said arms being formed with openings receiving said rod therethrough, a member receiving and being slidably mounted on said arms, said member having a downwardly projecting tongue, and a strip of spring metal fixed to said tongue and having an upwardly extending portion, and a portion extending downwardly from the upper end of said first portion, a pair of doll's eyes received within said sockets and being mounted on the ends of a bridge, and said downwardly extending portion of said spring strip engaging said bridge.
12. In combination with a doll's head provided with a pair of eye sockets, a horizontal rod fixed within said head and having the ends thereof engaging the side walls of said head, said head being formed with a recess on the inner surface thereof in back of the forehead, a bifurcated member having a pair of parallel arms interconnected at one end, said interconnected end being received within said recess, and the outer ends of said arms being formed with openings receiving said rod therethrough, a member receiving and being slidably mounted on said arms, said member having a downwardly projecting tongue, a strip of spring metal fixed to said tongue and having an upwardly extending portion, and a portion extending downwardly from the upper end of said first portion, a pair of doll's eyes re-

ceived within said sockets and being mounted on the ends of a bridge, and said downwardly extending portion of said spring strip engaging said bridge, at least one of said parallel arms being formed with an opening, and a tab on said slidably mounted member adapted to be received within said opening to retain same against sliding movement on said arms. 5

13. In combination with a doll's head provided with a pair of eye sockets, a member slidably mounted within said head for movement from front to rear with respect to said head, a strip spring fixed to said member, a pair of doll's eyes mounted on a bridge, said spring having a channelled portion engaging said bridge for pressing 15 the eyes into said sockets and means to limit movement of the engaging portion of said spring relative to said slidably mounted member.

14. In combination with a doll's head provided with a pair of eye sockets, a horizontal rod fixed 20 within said head and having the ends thereof engaging the side walls of said head, a member having the front end thereof engaging the front of the doll's head and the rear end thereof engaging said horizontal rod, a member slidably 25 mounted on said first member, a strip of spring metal fixed to said slidably mounted member, a bridge having doll's eyes thereon received within said sockets and said strip having a channelled portion engaging said bridge for pressing the eyes 30 within said sockets and for limiting the downward movement of said bridge.

MATTEO DE CESARE.
DAVID COHN.
